(57) **CLAIM**

The ornamental design for an electrical connector, as shown and described.

DESCRIPTION

FIG. 1 is a front elevational view of an electrical connector; FIG. 2 is a top plan view thereof;

FIG. 3 is a bottom plan view thereof;

FIG. 4 is a rear elevational view thereof;

FIG. 5 is a left side elevational view thereof; and,
FIG. 6 is a front, top, and right side perspective view thereof.
A right side elevational view of the electrical connector is omitted because it is presented symmetrical to the left side elevational view of FIG. 5.

The broken line showing of the environment is for illustrative purpose only and forms no part of the claimed design.
